DESIGN FOR A COMBINATION DESK CALENDAR AND MEMORANDUM PAD UNIT

Harold G. Davis, Brooklyn, N. Y.

Application April 7, 1948, Serial No. 145,576

Term of patent 14 years

(Cl. D74—5)

To all whom it may concern:

Be it known that I, Harold G. Davis, a citizen of the United States, residing at Brooklyn, in the county of Kings and State of New York, have invented a new, original, and ornamental Design for a Combination Desk Calendar and Memorandum Pad Unit, of which the following is a specification, reference being had to the accompanying drawing, forming part thereof.

Fig. 1 is a perspective view of a combination desk calendar and memorandum pad unit showing my new design;

Fig. 2 is a perspective view thereof with the calendar pad and memoranda sheets removed for convenience of illustration;

Fig. 3 is a front elevational view of Fig. 2;

Fig. 4 is a side view of Fig. 3, the side not shown being substantially the same as the one shown.

I claim:

The ornamental design for a combination desk calendar and memorandum pad unit, as shown and described.

HAROLD G. DAVIS.
